Stainless Steel Roll Up Shutter Doors Xinyi door <https://www.xinyidoorindustry.com/products/stainless-steel-rolling-door.html> Nov. 6, 2020 (Year: 2020)*

Primary Examiner — Leanne Was-Englehart

(74) Attorney, Agent, or Firm — Jose Cherson Weissbrot

(57) **CLAIM**

The ornamental design for a shutter door, as shown and described.

DESCRIPTION

FIG. 1 is a front perspective view of a shutter door showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

Broken lines in the drawings depict portions of the shutter door that form no part of the claimed design.
